Primary Examiner — Prabhakar Deshmukh

CLAIM

The ornamental design for a slatwall extrusion, as shown and described.

DESCRIPTION

FIG. 1 is a front perspective view of a slatwall extrusion showing my new design;

FIG. 2 is a front elevation view thereof;

FIG. 3 is a rear elevation view thereof;

FIG. 4 is a right side view thereof, which is a mirror image of the left side view;

FIG. 5 is a top plan view thereof; and,

FIG. 6 is a bottom plan view thereof.

The claimed design is cut on one side to indicate indefinite length.
